LUMINOUS LOCK ATTACHMENT

Filed Oct. 24, 1951

FIG. 1 FIG. 2

UNITED STATES PATENT OFFICE

2,658,151

LUMINOUS LOCK ATTACHMENT

Bernard Heinz, Scranton, Pa.

Application October 24, 1951, Serial No. 252,857

8 Claims. (Cl. 250—76)

1

This invention relates to a luminous attachment for locks.

An object of this invention is to provide a luminous attachment for locks, particularly vehicle door locks which will provide for easy spotting of the lock in the dark and which will assist in guiding the key into the keyhole.

Another object of this invention is to provide a luminous attachment for door locks which can be applied without changing the present structure of the lock, the attachment being secured to the lock by cementitious material.

A further object of this invention is to provide a luminous attachment which includes a rotatable key guide which is frictionally held against rotation so that the keyhole therethrough will be in registry with the keyhole of the lock.

With the above and other objects in view, my invention consists in the arrangement, combination and details of construction disclosed in the drawings and specification, and then more particularly pointed out in the appended claims.

In the drawing:

Figure 1 is a front elevation of a luminous lock attachment constructed according to an embodiment of this invention.

Figure 2 is a detailed side elevation of the device.

Figure 3 is a sectional view on an enlarged scale taken on the line 3—3 of Figure 1.

Figure 4 is a sectional view through the resilient ring for the key guide.

Figure 5 is a transverse sectional view of a modified form of this invention.

Referring to the drawing, the numeral 10 designates generally a conventional lock barrel which is encompassed in a cylindrical housing 11 having an outer barrel retaining flange 12 overlying the outer end of the barrel 10. The lock barrel 10 includes an outer end plate 13 having a key hole 14 therethrough for permitting insertion of a key into the locking mechanism. The lock barrel with the casing 11 is of a type which is mounted in a door of a vehicle, and in order to provide a means whereby the outer end of the lock may be made visible in the dark, I have provided a transparent ring 15.

The ring 15 has an inner diameter substantially equal to the inner diameter of the retaining flange 12, and the ring 15 is formed at its inner end with a flange 16. The ring 15 is also provided with an annular groove 17 disposed in the inner end thereof and within which a luminous material 18 is adapted to be disposed. The transverse configuration of ring 15 is such that the ring 15

2

will magnify the luminous material 18 so that there will appear to be a complete diffusion of the luminous material with respect to the ring 15. A collar, generally designated as 19, is secured by cementitious material 20 to the flange 12 and the collar 19 includes an inwardly flared ring 21 having an outer annular flange 22 engaging over the outer end of the casing 11.

10 A disc shaped key guide 23 is rotatably disposed within the ring 15, being provided with a keyhole 24 which is adapted to be normally disposed in registry with the keyhole 14. The outer side of the guide 23 inclines inwardly as indicated in 25 in the direction of the keyhole 24 so that when a key is being inserted through the keyhole 24, the key, upon striking the inclined surface 25, will automatically move inwardly toward the keyhole 24. The guide 23 is formed with an annular flange 26 at its inner end engaging against the inner end or side of the ring 15 so that ring 15 will retain guide 23 in operative position. Ring 15 with guide 23 is locked to the casing 11 by means of a locking collar generally designated as 27.

20 The locking collar 27 includes a cylindrical body 28 formed with a plurality of V-shaped slits 29, and the outer end of the cylindrical body 28 is formed with an inwardly extending annular flange 30 engaging over the flange 16 of ring 15. The series of circumferentially spaced apart slits 29 form a plurality of locking fingers 31, and each finger 31 is formed with an inwardly extending locking flange 32 adapted to engage behind the annular flange 22 of collar 19. The locking or retaining member 27 encompasses the ring 15 and the fixed collar 19, and in order to provide for frictionally holding key guide member 23 against rotation, resilient flat ring 33 is interposed between key guide 23 and fixed collar 19. Normally, the friction ring 33 is flat, as shown in Figure 4, but when the retaining collar 27 is applied to the fixed collar or ring 19, friction ring 33 will be flexed inwardly, as shown in Figure 3, so that key guide 23 will be under constant frictional engagement with ring 33 in order that guide 23 will be held against rotation.

30 In the application or mounting of the attachment on the lock structure embodying the barrel 10, which is positioned within the casing 11, the fixed collar 19 is cemented or otherwise fixedly secured to the casing 11 and the flange 12. The luminous ring 15 with the guide 23 disposed therein is positioned within the retaining ring 27, and the frictional ring 33 is disposed at the inner end of the guide 23. The retaining ring 27, which

is formed with a flared inner end 34, is pressed over the fixed ring 19 until the locking lugs or flanges 23 engage against the inner end of flange 22. At this time, friction ring 33 will be bent or flexed inwardly so as to assume a substantially frustoconical configuration with the outer marginal portion of ring 33 bearing against the outer marginal portion of collar 19, thereby placing ring 33 under tension and frictionally holding guide 23 against rotation.

Referring now to Figure 5, there is disclosed a modified form of this invention wherein a luminous ring 15a is provided with a groove 17a at its inner end within which a luminous material 18a is positioned. The ring 15a is formed at its inner end with a marginal flange 16a. A fixed or base collar generally designated as 19a is secured by cementitious material 20a to the lock casing 11a, and the base collar or ring 19a is formed of a frustoconical body 21a with an annular flange 22a encompassing the casing 11a.

A key guiding member 23a is rotatably disposed within ring 15a and is provided outwardly from the inner end thereof with an annular flange 35. A friction ring 36 is disposed loosely about the inner end of the guide 23a and bears against the flange 35. The ring 36 is normally flat and is adapted when the ring 15a is disposed in assembled and operative position to bend inwardly in substantially frustoconical configuration so as to bear resiliently and frictionally against flange 35, thereby holding the key guide 23a against rotation.

A retaining ring or collar 37 is formed of a cylindrical body 38 with an inwardly extending annular flange 39 bearing against the outer side of flange 16a. The cylindrical member 22a is exteriorly threaded and the interior of cylindrical body 38 of retaining member 37 is interiorly threaded for threaded engagement on the body or ring 22a so as to firmly secure the retaining ring 37 on the fixed collar 19a and hold the parts in assembled and operative position. The exterior of retaining member 37 may be knurled or otherwise roughened so as to facilitate the threading or unthreading of retaining member 37 on the fixed collar 19a. The luminous ring 15a is preferably formed out of transparent, plastic material, and the key guiding member 23a may also be formed out of plastic which may be either transparent or translucent.

What is claimed is:

1. A luminous attachment for a cylindrical lock barrel comprising a flanged collar engageable about the outer end of said barrel, cementitious means securing said collar on the outer end of said barrel, a luminous ring outwardly of and concentric to said collar, a key guide within said ring, a flange carried by said guide bearing against the inner end of said ring, means securing said ring to said collar, and a resilient ring interposed between said guide and said collar for resiliently and frictionally holding said guide against rotation.

2. A luminous attachment for a cylindrical lock barrel comprising a flanged collar engageable about the outer end of said barrel, cementitious means securing said collar on the outer end of said barrel, a luminous ring, an outer flange car-

ried by said ring, a cylindrical retainer, an inwardly extending flange carried by said retainer engaging about said outer flange, and resilient locking fingers carried by said retainer engaging about said collar.

3. A luminous attachment for a cylindrical lock barrel comprising a flanged collar engageable about the outer end of said barrel, cementitious means securing said collar on the outer end of said barrel, a luminous ring, an outer flange carried by said ring, a cylindrical retainer encompassing said flange and formed of a plurality of hook-shaped fingers engaging over said collar.

4. A luminous attachment for a cylindrical lock barrel comprising a flanged collar engageable about the outer end of said barrel, cementitious means securing said collar on the outer end of said barrel, a luminous ring, an outer flange, a circular retainer encompassing said flange, and cooperating threads carried by said collar and said retainer.

5. A luminous attachment for a cylindrical lock barrel comprising a flanged collar engageable about the outer end of said barrel, means securing said collar on the outer end of said barrel, a luminous ring outwardly of and concentric to said collar, a key guide within said ring, a flange carried by said guide bearing against the inner end of said ring, means securing said ring to said collar, and a resilient ring interposed between said guide and said collar for resiliently and frictionally holding said guide against rotation.

6. A luminous attachment for a cylindrical lock barrel comprising a flanged collar engageable about the outer end of said barrel, means securing said collar on the outer end of said barrel, a luminous ring, an outer flange carried by said ring, a cylindrical retainer, an inwardly extending flange carried by said retainer engaging about said outer flange, and resilient locking fingers carried by said retainer engaging about said collar.

7. A luminous attachment for a cylindrical lock barrel comprising a flanged collar engageable about the outer end of said barrel, means securing said collar on the outer end of said barrel, a luminous ring, an outer flange carried by said ring, a cylindrical retainer encompassing said flange and formed of a plurality of hook-shaped fingers engaging over said collar.

8. A luminous attachment for a cylindrical lock barrel comprising a flanged collar engageable about the outer end of said barrel, means securing said collar on the outer end of said barrel, a luminous ring, an outer flange, a circular retainer encompassing said flange, and cooperating threads carried by said collar and said retainer.
